(57) **CLAIM**

The ornamental design for a mop head ply as shown and described.

DESCRIPTION

FIG. 1 is a top perspective view showing a first embodiment of my new design for a mop head ply;

FIG. 2 is another top perspective view of the design of FIG. 1;

FIG. 3 is a right side elevational view of the design of FIG. 1, wherein the left side elevational view is the same as the right side elevational view;

FIG. 4 is a front elevational view of the design of FIG. 1, wherein the rear elevational view is the same as the front elevational view;

FIG. 5 is a top plan view of the design of FIG. 1;

FIG. 6 is a bottom plan view of the design of FIG. 1;

FIG. 7 is a top perspective view showing a second embodiment of my new design for a mop head ply;

FIG. 8 is another top side perspective view of the design of FIG. 7;

FIG. 9 is a right side elevational view of the design of FIG. 7, wherein the left side elevational view is the same as the right side elevational view;

FIG. 10 is a front elevational view of the design of FIG. 7, wherein the rear elevational view is the same as the front elevational view;

FIG. 11 is a top plan view of the design of FIG. 7; and,

FIG. 12 is a bottom plan view of the design of FIG. 7. The broken lines shown represent environmental structure and portions of the mop head ply that form no part of the claimed design.

The dashed curved break lines shown in FIGS. 1, 2, 4-8, and 10-12 are symbolic breaks indicative of a variable distance therebetween, and the appearance of any portion of the mop head ply between the break lines forms no part of the claimed design.
